MEANS FOR OPERATING GATES.

1,073,552.

Specification of Letters Patent. Patented Sept. 16, 1913.

Application filed January 4, 1913. Serial No. 740,132.

To all whom it may concern:

Be it known that I, CHARLES W. WITSIL, a citizen of the United States, and a resident of East Stroudsburg, in the county of 5 Monroe and State of Pennsylvania, have invented a new and Improved Means for Operating Gates, of which the following is a full, clear, and exact description.

The present invention is designed more 10 particularly as an improvement in the gate-operating means forming the subject of Letters Patent No. 1,043,654 granted to me November 5, 1912, and has for its design to improve the said means in various particulars, to the end that convenience and efficiency in operation may be promoted, as well as economy of manufacture and simplicity of adjustment.

The invention will be particularly explained in the specific description herein-after to be given.

Reference is to be had to the accompanying drawing forming a part of this specification, in which the figure is a perspective view of a gate provided with my improved operating means.

In the practical embodiment illustrated any approved hinge post 10 is provided, to which the gate 11 is hinged; a latch post 12 30 having a catch 13 to be engaged by a latch 14 on the gate; and road posts 15 at each side of the hinge post 10, said road posts being provided with catches 13^a to engage the latch 14. It is to be understood that the 35 term "road post" and the form of the post is not of moment, since any equivalent structure will answer.

The gate is adapted to be swung on its 40 hinges by operating ropes or equivalent flexible elements 16, which may be continuous with each other; they are secured, to a drum 17 appurtenant to the gate hinge, and extend in opposite directions from said drum, over idlers 19 carried at the tops of the 45 road-posts 15, and to a connection with operating levers 20 fulcrumed at one end on said posts, as at 20^a, and provided with a suitable handle 21 at the free end of each lever, the handle in the present instance being 50 shown as consisting of a laterally bent arm. The connection between an operating rope 16 and a lever 20 is preferably effected by securing the end of the rope to an eye 55 on the shank 23 having a hook 24 passing through an orifice 20^b in the lever, so

that there is a relative turning movement between the shank and the lever, to relieve the shank of strain by permitting it to assume a position substantially in line with the end of the operating rope when the lever is swung vertically on its fulcrum 20^a. 60

The latch 14 is adapted to be tripped by a latch bar 25, which ranges longitudinally of the gate 11, being pivoted intermediate its ends as at 25^a, to any convenient member 26 of said gate. The inner end of the latch bar 25 extends adjacent to the hinge end of the post and is provided with a weight 27 normally tending to lower that end of the bar, there being any suitable 70 stop 28 on the gate to limit the downward movement of the latch bar. Attached to the inner end of the latch bar, preferably by a connection with the weight 27, is a latch string 29, having branches 30 that are bent 75 around a vertical drum 31 in fixed relation to the drum 17, said branches 30 of the latch string extending in opposite directions from the drum 31 toward the road posts 15. The outer end of each latch string 30 is secured 80 to a pull rod 32 adapted to slide in lugs 20^c on the lever 20, the pull rod terminating at its outer end in a lateral arm 33, constituting a finger-piece parallel with the handle 21 of the lever 20, so that when the lever 85 handle is grasped, the finger of the operator may conveniently engage the arm 33 of the pull rod, for exerting a pull on the latch string. A coil spring 34 surrounds the pull rod 32, between the lugs 20^c and for returning the pull rod after a sliding movement 90 by the finger of the operator. Preferably there is formed on the drum 17, a peripheral flange 35 below the operating ropes 16, to guide said ropes, and a peripheral flange 95 36 at the upper end of the drum, for a similar purpose.

The latch 14 is fulcrumed at a point between its ends to rock vertically on its pivot pin 71, which passes through the front upright 100 11^b of the gate. The gate as shown is formed of tubing, and said front upright is received in a lateral recess 72 in the latch 14, the pivot pin passing through the said upright, through the inner wall of the recess 105 72, and through a cap plate 73, which closes the outer end of the said recess, and is suitably secured.

The latch bar 25 is provided at its outer end with a lateral stud 25^b disposed above 110

the inner end of the latch 14, which is in the form of an arm 75, and a retractile spring 76 is connected at its lower end with the arm 75 of the latch, and at its upper end with the top bar of the gate 11, or other convenient member of the gate, to normally raise said latch arm and depress the outer end 14^a of the latch, to engage the latter with the catch 13 or one of the catches 13^a.
10 Preferably the end 14^a of the latch is weighted, by giving it increased thickness, and its sides are beveled, converging toward the bottom edge to be received in a similar depression 13^b in the catch.
15 With the described construction, an occupant of a vehicle approaching the gate in either direction, may grasp the adjacent lever 20 by the handle 21 and also grasp the arm 33 of the pull rod 22, to exert a pull on
20 said rod 32 and on the latch string, which will raise the inner end of the latch bar or latch trip bar 25, depressing its outer end to cause the trip stud 25^b to depress the arm 75 of the latch 14 and raise said latch out of
25 engagement with the catch 13. The latch having thus been released, the lever is swung down on its fulcrum and the operating rope 16 will thus swing the gate away from the operator until the latch 14 engages
30 the catch plate 13^a of the distant road post 15. The wagon having passed through the gate, the occupant may swing the other lever 20 downward to close the gate.

The described arrangement of the operating ropes, the latch strings, lever, and the pull rods for the latch, it will be seen, enables a person to release the latch and operate the gate with the greatest convenience; the parts provide a simple and inexpensive construction and minimize the possibility of the parts getting out of order.

Having thus described my invention, I claim as new, and desire to secure by Letters Patent:

45 1. A gate-operating means comprising, in combination with the gate, gate posts and

road posts, idlers on the road-posts, operating ropes extending over the idlers, a lever fulcrumed on each road post, rope-connecting members to which the ropes are secured, 50 said members being mounted on the levers between the fulcrums and the free ends, a gate latch, a latch-tripping device on the gate, a latch string connected with the latch-tripping device and having branches extending in opposite directions to the levers on the road posts, a pull-rod carried by each lever to move bodily therewith in the movement of the lever, one end of the pull rod being secured to the latch string and the opposite end having the form of a handle located sufficiently close to the end of the lever for both to be grasped by one hand, and a retractile spring for restoring the pull-rod to its original position after an operating 60 movement.

2. The combination with a hinged gate, gate posts and road posts, of gate-operating ropes extending from the gate in opposite directions to the road posts, levers to which 70 said ropes are secured, the levers being fulcrumed on the road posts, a latch, a latch-tripping device, a latch string connected with said tripping device and branching in opposite directions to the levers, a longitudinally sliding pull rod on each lever, each lever having guide lugs in which the pull rod has movement, a spring between said lugs and serving to return the pull rod to the original position after movement thereof, the lever and the pull rod having lateral handle members approximately parallel with each other and sufficiently close to be both grasped by the hand of the operator.

In testimony whereof I have signed my 85 name to this specification in the presence of two subscribing witnesses.

CHARLES W. WITSIL.
